KNOB AND SHAFT CONSTRUCTION

Newton C. Schellenger, Elkhart, Ind., assignor to
 Chicago Telephone Supply Company, Elkhart,
 Ind., a corporation of Indiana

Application November 22, 1937, Serial No. 175,798

3 Claims. (Cl. 287—53)

This invention relates to a new and improved knob and shaft construction and more particularly to such a construction especially adapted for use with radio set or test instrument controls or the like.

The methods in commercial use for securing knobs to shafts with such apparatus have consisted of two general types. The most usual type comprises a set-screw threaded in a knob and for maximum efficiency this requires a solid shaft with a flattened face to receive the set-screw. The other type comprises several modifications all of which include springs carried either by the shaft or by the knob. Both types require additional parts other than the knob and shaft, such as set-screws or springs.

It is an object of the present invention to provide a new and improved knob and shaft construction.

It is a further object to provide a construction of this character in which the knob is secured to the shaft without the use of additional parts.

It is also an object to provide a construction in which an inexpensive sheet metal shaft may be used.

It is an additional object to provide a construction in which the shaft and knob are positively keyed to rotate together.

Other and further objects will appear as the description proceeds.

I have shown a preferred embodiment of my invention in the accompanying drawing, in which—

Figure 1 is an elevation of a control with my improved knob and shaft applied thereto;

Figure 2 is a sectional view showing the shaft end and knob in unassembled relation;

Figure 3 is a section taken on line 3—3 of Figure 1; and

Figure 4 is an end view of the shaft.

Referring first to Figure 1, the control housing 11 may enclose a device such as a switch or a variable resistance which is actuated or varied by the rotation of the shaft 12 which extends through the threaded bushing 13 by means of which the device may be secured to a chassis or panel or the like. The knob 14 is secured upon the end of the shaft.

As clearly shown in the drawing, the shaft is made of sheet metal which is rolled to form a tubular member with the edges of the sheet adjacent each other. These edges are sloped apart as shown at 15 adjacent the free end of the shaft to form a tapering, wedge-shaped recess. The knob 14 is provided with the substantially cylind-

rical inner opening 16, adapted to fit over the end of the shaft 12. The inner face of this opening 16 carries the securing lug 17 which is similar in form to the tapering recess 15 in the end of the shaft.

The knob is assembled upon the shaft by moving it axially onto the shaft with the lug 17 in registration with the recess 15 in the shaft wall. It may be firmly seated by means of a light blow from a rubber or rawhide hammer or merely by being struck with the heel of the hand.

The sheet metal of the shaft is sufficiently resilient so that the knob is held firmly in place. The wedging action of the lug 17 in the recess 15 serves to expand the shaft circumferentially so that it positively engages the wall of the opening 16. The knob may be removed by loosening it by a blow on the side or directed slightly outward from the control to which the shaft is connected. The securing action of the wedge lug 17 has no tendency to compress or distort the shaft as is the case when set-screws are used to secure knobs to hollow shafts. When a knob of this type is secured to a hollow shaft having other control means extending through the opening in the shaft, there is no tendency to bind the inner control. The action of the knob securing wedge expands the shaft rather than contracts it. The edges of the split in the shaft may be slightly roughened as the material is cut to form the split. This roughened edge will bite into the wedge and assist in preventing undesired separation of the parts after assembly.

Hollow shafts of this character require considerably less metal than solid shafts of the same size, and since the shafts of controls are often formed of copper bearing alloys, the saving in metal cost may be considerable in quantity production.

In addition to this a substantial saving is effected in the time and expense of making the complete shaft from the raw material as my construction requires only a simple and quick punch press operation whereas the conventional solid shaft requires relatively difficult and slow operations in both automatic screw machines and milling machines.

While I have shown a preferred form of construction, this is to be understood to be illustrative only. It will be understood that the knob 50 may have any desired form or construction. The lug 17 may be formed integrally with the knob which consists of Bakelite or other similar material. The lug 17 may, however, if desired, be made of metal and inserted in the knob during

the molding operation or secured therein in any desired manner. I contemplate such other changes and modifications as come within the spirit and scope of the appended claims.

I claim:

- 5 1. In combination: a cylindrical tube slit longitudinally from end to end and formed of resiliently deformable metal with the edges of the slit in juxtaposition; a knob having a substantially cylindrical cavity to loosely receive an end portion of the tube, and means in said cavity for expanding the tube into firm engagement with the side wall of the cavity as it is inserted to thereby removably secure the knob to the tube.
- 10 16 2. In combination: a cylindrical tube slit longitudinally from end to end and formed of resiliently deformable metal with the edges of the slit in juxtaposition; a knob having a substantially cylindrical cavity to loosely receive an end portion of the tube; and a wedge shaped lug on
- 15 20 the side wall of the cavity adapted to be forced into the slit during the application of the knob to

the tube to spread apart the edges of the slit and expand the tube into firm frictional engagement with the side wall of the cavity as it is inserted to thereby removably and nonrotatably secure the knob to the tube.

3. In combination: a cylindrical tube slit longitudinally from end to end and formed of resiliently deformable metal with the edges of the slit in juxtaposition, the marginal portions of the slit at one end thereof being cut away to provide an outwardly flaring mouth for the slit; a knob having a substantially cylindrical cavity to loosely receive said end portion of the tube; and a lug on the side wall of the cavity positioned to enter the flaring mouth of the slit during application of the knob to the tube to spread apart the edges of the slit and thereby expand the tube into firm frictional engagement with the side wall of the cavity as it is inserted to removably and nonrotatably secure the knob to the tube.

NEWTON C. SCHELLENGER.
